UNITED STATES PATENT OFFICE

103,141

DESIGN FOR A COMPOUND TOOL

Edward L. White, San Angelo, Tex.

Application October 10, 1936, Serial No. 65,251

Term of patent 7 years

To all whom it may concern:

Be it known that I, Edward L. White, a citizen of the United States, residing at San Angelo, in the county of Tom Green and State of Texas, have invented a new, original, and ornamental Design for a Compound Tool, of which the following is a specification, reference being had to the accompanying drawing, forming part thereof.

The figure is a perspective view of a compound tool showing my new design.

The dominant ornamental features of the

present invention are resident in the upper and lower lateral projections from the shaft of the tool, the upper projection cooperating with the oppositely directed hook, and the lower projection curving in a direction opposite that of the said hook in a cooperative balancing function, leading to a unified appearance as a whole.

I claim:—

The ornamental design for a compound tool as shown and described.

EDWARD L. WHITE.
